G. C. SHACKLEFORD, P. J. GORDON & A. K. McMILLEN.
CONTINUOUS HEATING FURNACE.
APPLICATION FILED FEB. 8, 1912.

1,027,915.

Patented May 28, 1912.

UNITED STATES PATENT OFFICE.

GIBBON C. SHACKLEFORD AND PETER J. GORDON, OF YOUNGSTOWN, OHIO, AND ALBERT K. McMILLEN, OF SHERIDAN, PENNSYLVANIA.

CONTINUOUS HEATING-FURNACE.

1,027,915.

Specification of Letters Patent.

Patented May 28, 1912.

Application filed February 3, 1912. Serial No. 675,297.

To all whom it may concern:

Be it known that we, GIBBON C. SHACKLEFORD and PETER J. GORDON, both of Youngstown, in the county of Mahoning and State 5 of Ohio, and ALBERT K. McMILLEN, of Sheridan, in the county of Lebanon and State of Pennsylvania, have invented certain new and useful Improvements in Continuous Heating-Furnaces; and we do hereby declare the following to be a full, clear, and exact description of the invention, such as will enable others skilled in the art to which it appertains to make and use the same.

15 This invention relates to that class of continuous heating furnaces wherein the ingots or billets are automatically discharged from the zone of highest heat, and the primary object of our invention is to enable the heat 20 to be concentrated and intensified at or near the point of discharge or to be distributed generally throughout the furnace, according as conditions may require.

The invention will be hereinafter fully 25 set forth and particularly pointed out in the claims.

In the accompanying drawings, Figure 1 is a vertical longitudinal sectional view. Fig. 2 is a horizontal sectional view. Fig. 30 3 is a side elevation of the fuel attachment.

We have shown our invention applied to a known-type of furnace which embodies the usual track 1 extending longitudinally of the heating chamber 2 from the charging 35 inlet 3 to the discharge outlet 4, the track being inclined at 5 to effect the automatic discharge of the billets from the furnace when in the zone of highest heat. The billets are pushed along the tracks by pushing mechanism of known construction. At 40 its discharging end the heating chamber is in communication with a mixing chamber 6, both chambers being in longitudinal alinement. The floor 7 of the mixing chamber 45 is shown as being inclined upwardly, its raised end being adjacent to the discharge outlet above which it and the entire mixing chamber are shown as supported by suitable structural beams.

50 The air and gas are fed into the mixing chamber in line with the heating chamber. The air is introduced through nozzles 8, and the gas through nozzles 9, and both project into openings in the end wall of the mixing chamber. We have shown three air

nozzles and a corresponding number of gas nozzles, the former leading from an air-supply box 10, and the gas nozzles from a gas-supply box 12. Air is supplied to box 10 by pipes 13, and gas to box 12 by pipes 60 14. Each nozzle 8 is shown as having at its receiving end an ordinary inlet valve 15, and each nozzle 9 a similar valve 16. These valves regulate the volume of air and gas admitted to the furnace. 65

For the purpose of controlling the direction of the air and gas, that is to say, the plane of the direction thereof into the mixing and heating chambers, each nozzle is equipped with deflecting means within the control of the operator. In each nozzle 8 we locate a deflector 17, and in each nozzle 9 a deflector 18, respectively controlled by levers 19 and 20. Under normal conditions the deflectors 18 will lie on the bottoms of 70 the gas-nozzle so as to allow an uninterrupted flow of gas in substantially direct alinement with the mixing and heating chambers, and at the same time the air-deflectors 17 will be fully opened and lie 75 against the tops of the air-nozzles. 80

If, in practice, it be found that the ingots or billets have not attained the necessary temperature before being discharged, this result may be secured by intensifying as 85 well as concentrating the flame on the ingots just before they reach the inclined track. This is accomplished by lowering the air deflectors 17 a few inches, as indicated in dotted lines, Fig. 1. This will result in concentrating on the ingots near the point of discharge a very intense flame which will quickly bring the steel up to the desired heat. If, on the other hand, it is found that the steel is being heated to too 90 great a degree at or about the point of discharge, the operator raises the air-deflectors 17 against the tops of the air nozzles and at the same time raises the gas-deflectors 18 about half way as shown in dotted lines, Fig. 1. This will result in the gaseous fuel being directed against the roof of the heating chamber and over the billets near the discharge outlet, and the heat will be thrown back into the chamber toward the charging inlet. Within certain limits the extent to which the heat may be thus thrown back into the heating-chamber is controlled by the operator by merely adjusting the gas-deflectors. 95 100 105 110

We claim as our invention:

1. In a continuous heating furnace having a charging inlet at one end and a discharge outlet at or near the other end, supports for ingots or billets extending through the heating chamber from the charging inlet to the discharge outlet, a mixing chamber in alignment with said heating chamber, means for admitting gas to said mixing chamber in line with the heating chamber, means for likewise admitting air to said mixing chamber, and means for regulating the plane of admission of the air and gas to the heating chamber.
- 10 2. In a continuous heating furnace having a charging inlet at one end and a discharge outlet at or near the other end, supports for ingots or billets extending through the heating chamber from the charging inlet to the discharge outlet, a mixing chamber in alignment with said heating chamber, means for admitting gas to said mixing chamber in line with the heating chamber, means for likewise admitting air to said mixing chamber, and means for regulating the plane of entrance of the air.
- 15 3. In a continuous heating furnace having a charging inlet at one end and a discharge outlet at or near the other end, supports for ingots or billets extending through the heating chamber from the charging inlet to the discharge outlet, a mixing chamber in alignment with said heating chamber, means for admitting gas to said mixing chamber in line with the heating chamber, means for likewise admitting air to said mixing chamber, and means for regulating the plane of entrance of the air.
- 20 4. In a continuous heating furnace having a charging inlet at one end and a discharge outlet at or near the other end, supports for ingots or billets extending through the heating chamber from the charging inlet to the discharge outlet, a mixing chamber in alignment with said heating chamber, means for admitting gas to said mixing chamber in line with the heating chamber, means for likewise admitting air to said mixing chamber, and means for regulating the plane of entrance of the gas.
- 25 5. In a continuous heating furnace having a charging inlet at one end and a discharge outlet at or near the other end, supports for ingots or billets extending through the heating chamber from the charging inlet to the discharge outlet, a mixing chamber in alignment with said heating chamber, air inlets in said mixing chamber in line with said heating chamber, gas inlets in said mixing chamber also in line with said heating chamber, one series of inlets being above the other, separate deflectors for the air and gas inlets, and means for operating such deflectors to regulate the plane of entrance of the gaseous fuel into the mixing and heating chambers.

In testimony whereof, we have signed this specification in the presence of subscribing witnesses.

GIBBON C. SHACKLEFORD.
PETER J. GORDON.
ALBERT K. McMILLEN.

Witnesses to signatures of Gibbon C. Shackleford and Peter J. Gordon:

PATRICK J. BARRETT,
